US00D779540S

(12) **United States Design Patent** (10) **Patent No.:** **US D779,540 S**
Rad et al. (45) **Date of Patent:** **** Feb. 21, 2017**

(54) **DISPLAY SCREEN OR PORTION THEREOF WITH A GRAPHICAL USER INTERFACE OF A MOBILE DEVICE**

(71) Applicant: **Tinder, Inc.**, West Hollywood, CA (US)

(72) Inventors: **Sean Rad**, Los Angeles, CA (US);
Jonathan Badeen, North Hollywood, CA (US); **Christopher Paul Gulczynski**, Los Angeles, CA (US)

(73) Assignee: **Tinder, Inc.**, West Hollywood, CA (US)

(**) Term: **15 Years**

(21) Appl. No.: **29/560,824**

(22) Filed: **Apr. 11, 2016**

Related U.S. Application Data

(63) Continuation of application No. 29/465,628, filed on Aug. 29, 2013, now Pat. No. Des. 755,814.
